EDWARD W. MARVIN, OF BROOKLYN, NEW YORK, ASSIGNOR TO J. EDWARD OGDEN, OF BROOKLYN, NEW YORK.

DRAFT-HOOK.

1,209,739.

Specification of Letters Patent. Patented Dec. 26, 1916.

Application filed November 25, 1912. Serial No. 733,248.

To all whom it may concern:

Be it known that I, EDWARD W. MARVIN, a citizen of the United States, and a resident of Brooklyn, county of Kings, and State of New York, have invented certain new and useful Improvements in Draft-Hooks, of which the following is a specification, reference being had to the accompanying drawings, forming a part thereof.

10 My invention relates to draft hooks and it has for its object to provide a device of this character that shall be simple and durable in construction and adapted to support a load many times greater than that which can be sustained by devices of the same size and general character hitherto constructed.

I will describe my invention in the following specification and point out the novel features thereof in appended claims.

20 Figures 1 and 2 are elevations at right angles to each other of a combined hook and sheave block which is constructed in accordance with my invention, the hooks being open in Fig. 1 and closed in Fig. 2.

25 Like characters of reference designate corresponding parts in all the figures.

Referring to Figs. 1 and 2 of the drawings, the structure here shown comprises a hook in the form of a metal clevis 35 which is the supporting member. One of the ends of this clevis forms an engaging arm 36. Its other end terminates in a laterally extending projection 37. The device further comprises another hook member 38 pivoted to the clevis. A sheave or pulley 39 may be supported between the arms of the clevis, and if desired a sheave block 40 may be provided which covers the clevis and partially incloses the sheave.

40 The sheave is pivotally mounted on a bolt 41 which extends laterally through the arms of the clevis and the sheave block as shown in Fig. 1. The sheave block comprises a pair of oval side members 42 and 43 and a pair of end spacing blocks 44 and 45. The side block 43 is divided and its lower end 46 is secured to a projection 47 of the hook 38. The upper end of the projection 47 is provided with a hole 48 which is adapted to receive the projection 37 of the clevis, the projection being provided with a hole 49 to receive a cotter pin or wedge in order to hold the hook and clevis closed.

When the hook is open as shown in Fig. 1

the lower end 46 of the block 43 together with the projection 47 of the hook are swung outwardly, permitting a rope or cable to be inserted in the sheave block. After the rope has been inserted and the hook 38 brought into engagement with a load the part 38 may be swung about its pivot to close the hook and the sheave block simultaneously and may be locked in its closed position by inserting a pin in the hole 49.

One of the advantages of the interlocking construction of my invention arises from the fact that if the hook is strained by an overload and bent thereby, it cannot be closed. This will show an attendant that the hook has been injured and should be replaced. 70

It is evident that the clevis 35 and the hook 38 constitute a pair of hooks each having an arm or projection which is adapted to coöperate with and support the end of the other hook. One of the hooks may be 75 adapted to receive a sheave block and sheave as shown in the drawings, or they may be similar to each other.

Variations in size and arrangement of parts may be effected within the spirit and 80 scope of my invention.

What I claim is:

1. The combination with a sheave block comprising a U-shaped frame having a hook supporting member with a supporting 85 projection at one end and a laterally projecting lug at the other and a sheave rotatably mounted between the arms of the U-shaped frame, of a hook pivotally connected to the supporting member having a perforated 90 projection adapted to receive the lug of the frame when the hook is loaded, the end of the hook and the end of the supporting projection of the supporting member being adapted to interlock whereby the supporting 95 member sustains a material proportion of the load on the hook independently of said pivotal connection.

2. The combination with a sheave block comprising a U-shaped frame having a hook 100 supporting member with a supporting projection at one end and a laterally projecting lug at the other and a sheave rotatably mounted between the arms of the U-shaped frame, of a hook pivotally connected to the supporting member having a perforated 105 projection adapted to receive the lug of the frame when the hook is loaded, the end of

the hook and the end of the supporting projection of the supporting member being provided with coöperating shoulders.

3. A pair of pivotally connected single hooks arranged on opposite sides of their connecting pivot, each having a rigid arm or projection adapted to coöperate with the end of the other hook, each pair of coöperating parts being respectively provided with a key 10 and slot.

4. A pair of pivotally connected single hooks arranged on opposite sides of their connecting pivot, each having a rigid sup-

porting projection adapted to interlock with the end of the other hook, one of the hooks 15 being provided with a sheave block and sheave, the supporting projection of the other being adapted to close the sheave block.

In witness whereof, I have hereunto set 20 my hand this 21st day of November in the year 1912.

EDWARD W. MARVIN.

Witnesses:

WILLIAM J. MONTGOMERY,
ERNEST W. MARSHALL.
